ENOCH RECTOR, OF NEW YORK, N. Y., ASSIGNOR TO WAUKESHA MOTOR COMPANY, OF WAUKESHA, WISCONSIN, A CORPORATION OF WISCONSIN

INTERNAL COMBUSTION ENGINE

Application filed March 20, 1923, Serial No. 626,255. Renewed January 28, 1927.

The invention relates to an improved means for firing the gaseous fuel charge in an internal combustion engine and more specifically relates to an improved form of gas passageway constituting part of the explosive chamber in the head of such an engine. It is an approved practice in firing charges in the explosive chamber of an internal combustion engine to fire the charge at a plurality of points, either simultaneously or preferably in rapid sequence, and this multiple firing of the charge is usually attained by providing a plurality of spark plugs organized to function in rapid sequence. Spark plugs possess certain well known objections and multiplying their number obviously increases their objectionable features and further, sequential, multiple firing instrumentalities of this type have not proven entirely satisfactory from a practical standpoint.

The present disclosure features the use of a single spark plug and in its operation otherwise follows conventional practice in order to inaugurate the flame propagation through the compressed gaseous charge in the explosive chamber. The primary object of the invention is to provide a simple form of supplemental firing instrumentality which will not possess the objectionable features of a spark-plug, and which will function automatically following the inauguration of the increased pressure caused by the firing of the spark plugs in order to ignite a different part of the fuel charge. Another object is to provide an instrument which will be free of moving parts and which will not require the use of any electrical or other force and which will be controlled in its operation by the spark plug or other initial igniting instrumentality.

It has been known in the art of firing internal combustion engine charges to utilize the compression on the charge resulting from the compression stroke of the piston to raise the temperature of a body of gas in a hot chamber to the firing point and thus cause the piston in its gas compression act to fire the charge automatically. This mode of firing the gas charge has not proven satisfactory, among other reasons due to irregularity in period of firing and to the frequent

failure of the ignitor to function at all. Aside from this some outside heating means, usually an exposed flame, is required to heat the gas chamber but such apparatus necessitates the use of exposed flames and flame devices on automotive equipment cannot pass the requirement of the fire underwriters. 55

Accordingly another object of the invention is to provide a simple form of fuel charge ignitor which does not require the use of flames, or in fact of any other source of heat except the heat normally present in the explosive chamber. On the contrary the present disclosure features an air cooled ignitor of the gas compression type in distinction from the usual heated ignitor. 65

Various other objects and advantages of the invention will be in part obvious from an inspection of the accompanying drawing and in part will be more fully set forth in the following particular description of one form of mechanism embodying my invention, and the invention also consists in certain new and novel features of construction and combination of parts hereinafter set forth and 75 claimed.

In the accompanying drawing:—

The figure is a sectional view taken axially through the upper portion of a piston cylinder of an internal combustion engine 80 equipped with a preferred embodiment of the invention.

In the drawing there is shown a piston cylinder 10 in which is slidably mounted a piston 11 which cylinder is closed at one end 85 by means of an end wall 12 constituting part of a head 13. The cylinder and head are provided with water jackets 14 and a valve controlled inlet 15 admits fuel to the explosive chamber formed between the wall 12 90 and the adjacent side of the piston 11. A spark plug 16 is positioned over the inlet 15 and in other respects the showing as thus far described is intended to represent conventional constructions. 95

The central portion of the head 13 is restricted to the single wall 12 to provide an air cooling pocket 17 surrounded by the water cooled wall 18 forming part of the water jacket. The portion 19 of the wall 12 out- 100

lining the bottom of the pocket 17 is provided with a threaded opening 20. A thin walled tube 21 has its inner, opened end 22 in screw threaded engagement with the opening 20; extends through the pocket 17 and projects beyond the outlines of the engine head for variable distances as hereinafter described. The outer end 23 of the tube is closed and the bore of the tube constitutes a compression chamber 24 directly opened to the explosive chamber and having relatively small volumetric capacity compared to the capacity of the explosive chamber when the piston is at the end of its compression stroke.

It is a feature of this disclosure that normally, or rather when the gas in the explosive chamber is under compression, the gas in the compression chamber will be at a temperature less than the temperature at which the gases in the explosive chamber are ignited and at a temperature such that the compression wave from the initial firing by the spark plug will cause the temperature of the gases at the mouth of the tube to be raised to their firing temperature.

In the operation of an internal combustion engine, the heat from the combustion in the explosive chamber, of course, rapidly heats the head and adjacent parts of the piston cylinder. In the present instance this heat is communicated to the compression tube to heat the gas contained therein. However, unless special efforts are made to reduce the temperatures of the gases in the compression tube, the device would function erratically in the manner which rendered the old flame heated igniters so objectionable. In the present disclosure the tube is air cooled by its contact with the external air and is somewhat cooled at its inner end due to the cooling effect of the adjacent water jacket. It therefore results that the compression tube must be designed to meet the requirement of the particular engine with which it is to be installed. If the tube is too short it will become excessively heated and will fire on the compression stroke of the piston, and on the contrary if it is too long the gases therein will be excessively cooled and the device will not function as an ignitor in the manner hereinafter described. It is therefore necessary to provide a tube of those dimensions which will maintain this thermostatic balance during the actuation of the engine so that it will not fire automatically simply due to normal compression but will fire under normal compression plus the compression caused by the initial firing by the spark plug at each cycle of operations.

In operation and with the proper proportioned tube the charge is fired by the single spark plug as is usual in such constructions. A compression wave is started through the gas charge from the spark plug and in advance of the front flame. This compression wave

further compresses the gas in the compression chamber to such an extent that it will raise the temperature of the gas therein to or above the firing point of the gases thus causing the generation of a second flame at the open end of the compression chamber. A second flame front is thus started through the charge from the mouth of the tube. It is obviously within the scope of the disclosure to provide a plurality of spark plugs and a plurality of the compression chambers herein disclosed in those cases where an extremely rapid flame propagation is desired. Due to the closed dome effect of the compression chamber the inert previously fired gases will be trapped in the closed end but this will tend to stabilize the physical condition of the gas in the compression chamber and when the length of the tube has been once fixed it will continue to function as an ignitor without further attention.

It has been found that knocking and pre-ignition has been eliminated, presumably due to the fact that a body of inert gas becomes trapped in the close end of the tube 21 and acts as a cushion to receive the peak of the compression wave at the start of the firing action.

The tube 21 is disposed substantially at right angles to the explosion chamber, as illustrated. Upon ignition of the fuel charge in the tube, a sheet of flame is projected downwardly across the advancing kinetic pressure wave and serves to neutralize such wave. In this manner, the kinetic pressure wave is neutralized, or reduced, to a very material extent resulting in much smoother operation of the engine, with a resulting increase in efficiency. In engines of large type, two or more tubes may be employed, as above stated, and these tubes will act to successively neutralize the kinetic pressure wave as it advances into the explosion chamber in the cylinder.

Having thus described my invention, I claim:

In an internal combustion engine, the combination of an explosion chamber, means for initially igniting the charge, and an unobstructed tube closed at its outer end and having its inner end opening into the chamber beyond the point of initial ignition of the charge in the direction of the cylinder.

Signed at New York city in the county of New York and State of New York this 1st day of March A. D. 1923.

ENOCH RECTOR.
